UNITED STATES PATENT OFFICE

ERNEST J. STANLEY, OF LOS NIETOS, AND CLAUDE H. TAYLOR, OF LOS ANGELES,
CALIFORNIA; SAID TAYLOR ASSIGNOR TO SAID STANLEY

OPERATING MECHANISM FOR HOODS

Application filed March 11, 1930. Serial No. 435,005.

This invention relates to masks or hoods such as are worn by electro-welding operators for protecting the face and eyes, the mask being provided with a sight aperture through which the operator observes the work, and the sight aperture having an overlying shield or dark glass for protecting the eyes, with the shield normally closed but adapted to be opened when unobstructed vision is desired.

It is the object of the invention to provide for opening the protecting shield of the sight aperture without use of the hands, thereby leaving both of the operator's hands free for manipulating the welding apparatus.

More particularly it is an object of the invention to provide an operating mechanism for the protecting shield extending to a point readily accessible to some part of the anatomy of the operator other than his hands, and adapted for engagement by said part of the anatomy for opening and closing the protecting shield.

It is a still further object of the invention to arrange the operating mechanism for the protecting shield inside the mask or hood so that it may be engaged and actuated by movement of some part of the operator's head, and preferably to actuate the operating mechanism by opening and closing the lower jaw.

It is a still further object of the invention to provide operating mechanism of extremely simple and practical construction and occupying but little space so that it may be readily positioned inside the hood, and including an actuating lever forming a seat for reception of the chin so that movement of the lower jaw will open and close the protecting shield.

It is a still further object of the invention to provide the operating mechanism with means for releasably holding it in position with the protecting shield either opened or closed, and to preferably adapt the operating mechanism for incorporation in a hood structure of novel design, or use as an attachment for a usual hood.

Further objects of the invention will be readily understood from the following description of the accompanying drawings in which:

Fig. 1 is a rear elevation of a hood constructed in accordance with the invention.

Fig. 2 is a vertical section on the line 2-2 of Fig. 1.

Fig. 3 is a fragmentary front elevation of a type of hood now in use, and showing the improved operating mechanism as an attachment therefor.

Fig. 4 is a fragmentary side elevation of the hood and operating mechanism which is shown in Fig. 3.

The mask or hood is of a type generally used by electro-welding operators, and comprises a vertically elongated and cross-sectionally substantially semi-circular hood 1 of a suitable stiff material adapted to extend around the front of the user's head and held in place by a suitable head-engaging frame.

The head-frame preferably comprises a stiff forehead engaging element 2 rigidly fixed to the inside of the hood, as for example by arms 3, and adapted to appreciably space the hood from the face of the user as shown in Fig. 2, and having a flexible brow band 4 connected to the arms 3 with a flexible band 5 extending over the top of the head and connected at its respective ends to the hood and to the rear of the brow band. The brow band 4 and the head band 5 are preferably adjustable so as to readily fit the supporting frame to the head of the user, and for this purpose the ends of the brow band slidably overlap and the head band adjustably overlies the overlapping ends of the brow band as shown in Fig. 1, with the bands held in relatively adjusted position by any usual fastening means such as is shown at 6. A usual flexible apron 7 for protecting the neck preferably depends from the hood 1.

A sight aperture 8 is formed in hood 1 in alignment with the eye, and a shield 9 permitting vision but of dark glass for protecting the eyes normally closes the sight aperture, but is adapted to be opened when unobstructed vision is desired.

In the form of the invention illustrated in Figs. 1 and 2 the protecting shield is slidable in a guide frame 10 mounted on the inside of the front of the hood which is preferably flat as shown at 11. The guide frame sur-

rounds sight aperture 8 and is suitably channeled for vertical sliding reception of the glass 9 which is preferably mounted in a channeled frame 12. The glass 9 is preferably insertable through an open end 13 of its frame 12; and the frame 12 is inserted in guide frame 10 through the open lower end of the latter. The protecting shield is preferably limited in its vertical sliding movement by closing the upper end of frame 10, and providing retractable spring clips abutments 14 at the open lower end of the frame.

When the shield 9 is at its upper limit of movement it overlies the sight aperture 8, and when moved downwardly in guide 10 it uncovers the sight aperture as shown in broken lines in Fig. 2; and in order to still protect the eyes when the shield 9 is opened, an auxiliary lens 15 which is of clear glass preferably overlies the sight aperture 8 in rear of the sliding shield 9. The glass 15 may be mounted in an auxiliary guide frame 16 which is formed on the back of frame 10, the frame 16 being suitably channeled for reception of glass 15 which is preferably inserted through the open lower end of the frame, with the glass preferably removably held in place by usual spring clips 17.

The shield 9 is opened and closed by an operating mechanism which is accessible to some part of the anatomy of the operator other than his hands, in order that the hands may be left free for work; and in the present instance the operating mechanism is arranged inside the hood 1 and is adapted for engagement by the operator's chin so that the protecting shield may be opened and closed by opening and closing the lower jaw.

As an instance of this arrangement a rod 20 is fixed to the frame 12 of the protecting shield and depends from guide frame 10 inside the hood with a lever 21 which is fulcrumed in the hood connected to rod 20 and provided with a seat 22 adapted for engagement by the operator's chin for swinging the lever. The lever is preferably bowed, and may be fulcrumed on a supporting frame which is fixed medially of its ends to the inside of hood 1 proximate to its lower end, with arms 23 of the frame extending rearwardly in transversely spaced relation and pivotally supporting the ends of the bowed lever as shown at 25. The chin engaging seat 22 is fixed to the swinging end of the bowed lever, and a rigid extension of the lever projects forwardly from the seat 22 as shown at 24 and is pivoted to the rod 20 as shown at 26.

The seat 22 has a depending and rearwardly projecting apron 27 adapted to extend under the operator's chin and at its upper end has a rearwardly and upwardly inclined abutment 28 which fits over the top of the chin so that when the lower jaw is closed the chin by engaging abutment 28 swings lever 21 upwardly so as to close the shield 9, and

when the lower jaw is opened the chin engages apron 27 for swinging the lever so as to open the protecting shield. The operating connecting is adapted for adjustment to fit the seat 22 to the chin of the user, and for this purpose the rod 20 may be provided with usual means, shown as an adjusting nut 29, for adjusting the length of the rod.

Means are provided for releasably holding the operating connection in shifted position for either opening or closing the protecting shield, and for this purpose a spring 30 is adapted for shifting of its axis from one side to the other of pivotal connections 25 so as to yieldably retain the lever 21 in either elevated or depressed position. As an instance of this arrangement one of the bowed ends of lever 21 may be extended rearwardly beyond its pivot 25 as shown at 31, with spring 30 connected at its respective ends to the extension 31 and to the proximate arm of supporting frame 23. The extension 31 is curved as shown in Fig. 2 so that when lever 21 is swinging forwardly the axis of the spring is below pivotal connection 25 and will thus yieldably hold the lever against depression in order to retain the protecting shield 9 in its closed position, and when the lever is depressed against the yielding tension of its spring, the axis of the spring is shifted so that it lies above pivotal connection 25 as shown by broken lines in Fig. 2, thereby yieldably holding the lever in position for opening the protecting shield.

As thus far described the operating mechanism is particularly adapted for incorporation in a hood structure at the time of manufacture, but it may also be arranged as an attachment for a hood of standard construction; and in Figs. 3 and 4 we have shown the operating mechanism as an attachment for that type of hood in which the protecting shield for the eyes is mounted in a hinged frame which is adapted to be swung upwardly or downwardly for closing or opening the sight aperture.

The hood 1^a and its supporting frame for engaging the head are constructed as previously described, and a frame 16^a is mounted in the sight aperture 8^a and projects inside and outside the hood. A clear glass 15^a for covering the eyes when the protecting shield is swung open, is preferably mounted in frame 15^a so as to overlie the sight aperture, and a frame 12^a for a protecting shield 9^a of dark glass, is mounted at the front of frame 16^a so that the shield 9^a normally overlies the sight aperture. The frame 12^a is hinged at its lower edge to the frame 16^a as shown at 40, so that frame 12^a may be swung downwardly and outwardly for uncovering the sight aperture; and the frame 12^a is normally swung to closed position by a spring 41, and

is provided with a finger-hold 42 for opening and closing the same.

In order to swing the frame 12^a without using the hands, a chin-actuated operating lever is mounted in hood 1^a but is not shown in the drawings since the construction is similar to that previously set forth, and a rod 20^a which is reciprocated by the lever as previously described, operatively engages actuating means which extends outwardly through the hood and is connected to frame 12^a for swinging the latter.

As an instance of this arrangement a bell crank lever 45 may be pivoted to one side of that portion of frame 16^a which extends into the hood, with operating rod 20^a connected to one arm of the bell crank lever, and a link 46 connected to the other arm of the bell crank lever and projecting outwardly through the hood for pivotal connection to an arm 47 which depends from frame 12^a. The arm 47 may be readily attached to frame 12^a, as for example by a threaded engagement, and extends below the lower hinged edge of the frame, with the link 46 extending through a suitable eyelet 48 in the hood 1^a so that swinging the bell crank lever by the reciprocation of rod 20^a will open and close the swinging frame 12^a. The spring 41 may be used if desired, or it may be removed if the chin-engaged operating lever which actuates rod 20^a is provided with spring means such as previously described for yieldably retaining the operating mechanism in position for either closing or opening the swinging frame 12^a.

We have thus provided extremely simple but practical means for opening and closing the protecting shield which overlies the sight aperture of a hood for the face, the operating connection being adapted for engagement by some part of the anatomy, preferably the chin, so that the protecting shield may be opened and closed without use of the hands, and the operating connection comprising either an attachment for a usual hood or being incorporated in a hood structure at the time of manufacture.

We claim:

1. In combination, a hood for the face having a sight aperture, a transparent protecting shield for the sight aperture adapted to be opened and closed, a rod adapted for reciprocation in the hood for opening and closing the protecting shield, a lever pivoted in the hood and operatively connected to the rod, a seat on the lever adapted for engagement by the chin of the user for swinging the lever by opening and closing the lower jaw, and a spring connected to the lever and adapted for shifting of its axis to one side or the other of the pivotal mounting for the lever for yieldably holding the lever when swung to position for either opening or closing the protecting shield.
2. In combination, a hood for the face hav-

ing a sight aperture, a shield adapted for vertical sliding movement relative to the hood for opening or closing the sight aperture, a rod depending from the shield and adapted for vertical reciprocation in the hood adjacent its front wall, a lever in the hood having a portion extending transversely of the hood adjacent its front wall and terminating at its end in an arm extending rearwardly in the hood adjacent its side wall, the lever being pivoted relative to the hood adjacent the rear end of the arm so that the transverse portion of the lever is adapted for vertical swinging movement, said transverse portion of the lever being operatively connected to the rod, and a seat on said transverse portion of the lever adapted for engagement by the chin of the user for swinging the lever by opening and closing the lower jaw.

3. In combination, a hood for the face having a sight aperture, a shield adapted for vertical sliding movement relative to the hood for opening or closing the sight aperture, a rod depending from the shield and adapted for vertical reciprocation in the hood adjacent its front wall, a lever in the hood having a portion extending transversely of the hood adjacent its front wall and terminating at its end in an arm extending rearwardly in the hood adjacent its side wall, the lever being pivoted relative to the hood adjacent the rear end of the arm so that the transverse portion of the lever is adapted for vertical swinging movement, said transverse portion of the lever being operatively connected to the rod, a seat on said transverse portion of the lever adapted for engagement by the chin of the user for swinging the lever by opening and closing the lower jaw, and means for yieldably retaining the lever in position with the protecting shield either opened or closed.

4. In combination, a hood for the face having a sight aperture, a shield adapted for vertical sliding movement relative to the hood for opening or closing the sight aperture, a rod depending from the shield and adapted for vertical reciprocation in the hood adjacent its front wall, a lever in the hood having a portion extending transversely of the hood adjacent its front wall and terminating at its end in an arm extending rearwardly in the hood adjacent its side wall, the lever being pivoted relative to the hood adjacent the rear end of the arm so that the transverse portion of the lever is adapted for vertical swinging movement, said transverse portion of the lever being operatively connected to the rod, a seat on said transverse portion of the lever adapted for engagement by the chin of the user for swinging the lever by opening and closing the lower jaw, and a spring connected to the lever arm and adapted for shifting of its axis to one side or the other of the pivotal mounting for the lever arm so as to yieldably

hold the lever in position with the protecting shield either opened or closed.

5. In combination, a hood for the face having a sight aperture, a shield for the sight aperture adapted to be opened and closed, means actuated by the chin of the user for opening and closing the shield, said actuating means including a pivoted lever, and a spring adapted for shifting of its axis to one side or the other of the pivotal mounting for the lever so as to yieldably hold the lever in position with the protecting shield either opened or closed.
